Specification for Design.

Patented Mar. 7, 1916.

Application filed January 3, 1916. Serial No. 69,920. Term of patent 3½ years.

To all whom it may concern:

Be it known that I, IRA M. CLARKE, a citizen of the United States of America, and residing in the city of Pittsburgh, in the county of Allegheny and State of Pennsylvania, have invented a certain new, original, and ornamental Design for a Candy Container or Bank, of which the following is a specification, reference being had to the accompanying drawing, which illustrates the design.

In the accompanying drawings, Figure 1 is a front elevation of a candy container showing my improved design, and Fig. 2 is a top plan view of the same.

I claim:

The ornamental design for a candy container or bank, as shown.

IRA M. CLARKE.
